UNITED STATES PATENT OFFICE.

WILLIAM A. LORENZ, OF HARTFORD, CONNECTICUT.

DESIGN FOR A CAN OR JAR.

SPECIFICATION forming part of Design No. 35,471, dated December 24, 1901.

Application filed August 12, 1901; Serial No. 71,846. Term of patent 14 years.

To all whom it may concern:

Be it known that I, WILLIAM A. LORENZ, a citizen of the United States, residing in Hartford, in the county of Hartford and State of Connecticut, have invented and produced a new and original Design for Cans or Jars, of which the following is a specification.

My design relates to the external contour of cans, jars, and similar receptacles.

In the drawings, in which similar numerals designate corresponding parts, Figure 1 is a top view, and Fig. 2 a side view, of a can or jar embodying my design.

The jar is approximately cylindrical in contour, the body portion 10 being surmounted by a top, which is smaller in diameter than the body and comprises the comparatively narrow annular bands or rings 11 and 12, the latter of which is smaller in diameter than

the former. These bands or rings are separated by an intervening peripheral groove 13, which is substantially semicircular in cross-sectional outline. A similar peripheral groove 14 separates the band 11 from the body 10 of the jar.

Having described my invention, what I claim as new, and desire to secure by Letters Patent, is—

The design for a can or jar substantially as shown and described.

In testimony whereof I have signed my name to this specification in the presence of two subscribing witnesses.

WILLIAM A. LORENZ.
